(57) CLAIM

We claim the ornamental design for a lipstick packaging, as shown and described.

DESCRIPTION

FIG. 1 is a perspective view of our new design for a lipstick packaging;

FIG. 2 is a front view thereof;

FIG. 3 is a rear view thereof;

FIG. 4 is a side view thereof (the left and right sides are mirror images of one another);

FIG. 5 is a top view thereof; and,

FIG. 6 is a bottom view thereof.
